UNITED STATES PATENT OFFICE.

WILLIAM H. WILKINSON, OF BROOKLINE, MASSACHUSETTS.

JACKKNIFE.

SPECIFICATION forming part of Letters Patent No. 633,931, dated September 26, 1899.

Application filed May 2, 1899. Serial No. 715,286. (No model.)

To all whom it may concern:

Be it known that I, WILLIAM H. WILKINSON, a citizen of the United States, residing at Brookline, in the county of Norfolk and State of Massachusetts, have invented new and useful Improvements in Jackknives, of which the following is a specification.

This invention relates to improvements in jackknives; and it has for its object to prevent the hinged portion of the blade from projecting above the handle, thus preventing the usual projection at such hinged portion from tearing the pocket when carried therein.

It also has for its object to enable the user to grasp and hold the handle while using the knife without injury or discomfort, and also to protect the pointed ends of the blades and prevent such ends from projecting above the butt-end of the handle, as will hereinafter be more fully shown and described, reference being had to the accompanying drawings, wherein—

Figure 1 represents a side elevation of my improved jackknife, showing the blades closed. Fig. 2 represents a top plan view of Fig. 1. Fig. 3 represents a longitudinal section on the line 3 3 shown in Fig. 2; and Fig. 4 represents a side elevation of the improved knife, showing one of the blades open.

Similar letters refer to similar parts wherever they occur on the different parts of the drawings.

In the drawings, A represents the knife-handle, on which A' is what is termed the "bolster," and A" the butt.

B B are the knife-blades, pivoted at C, as shown.

I make the width of the bolster of such a size relative to the hinged blades so that the upper edge of said bolster shall be even with the back of the knife-blades when the latter are closed, as shown in the drawings, thus making the bolster end of the handle sufficiently wide to conceal the hinged back ends of the knife-blades when closed and preventing any sharp corners on the blades from sticking up above the bolster, which are liable to tear the clothing when carried in the pocket.

ets of garments. The butt A" is extended upwardly above the middle portion of the handle, so as to properly conceal the pointed ends of the blades, and thereby enabling such pointed ends to be sharpened from time to time without causing such ends to project above the butt upper portion of the handle, as is a common objection to ordinary jackknives where the butt-end is not extended upwardly to cover and protect the pointed end of the blade.

D in Figs. 2 and 3 represents the longitudinal division-plate between the blades B B. Usually such division-plate extends upwardly even with the upper contour of the handle; but this is objectionable, as by grasping the handle such division-plate is liable to cause discomfort to the hand of the user, and to obviate such difficulty I terminate the upper edge of said division-plate at a proper distance below the upper contour of the handle, as represented in Fig. 3.

What I wish to secure by Letters Patent and claim is—

1. A jackknife provided with one or more hinged blades, a division-plate arranged between said blades and a handle extended outwardly beyond said division-plate, substantially as and for the purpose set forth.

2. A jackknife provided with one or more hinged blades combined with a handle having the interior bolster end arranged even with the back of the blade or blades, and having its butt portion extended beyond the middle part of the handle so as to serve as a shield or protector for the pointed end of the blade or blades and having a division-plate arranged between the blades, with the handle extending outwardly beyond said plate, substantially as and for the purpose set forth.

In testimony whereof I have hereunto set my hand in presence of two subscribing witnesses.

WILLIAM H. WILKINSON.

Witnesses:

ALBAN ANDREN,
JOHN A. JONES.
